UNITED STATES PATENT OFFICE

122,616

DESIGN FOR A LOOP ANTENNA HOUSING OR SIMILAR ARTICLE

William P. Lear, Dayton, Ohio assignor to Lear
Avia, Inc., Dayton, Ohio, a corporation of Illinois

Application July 20, 1940, Serial No. 93,802

Term of patent 14 years

To all whom it may concern:

Be it known that I, William P. Lear, a citizen of the United States, residing at Dayton, in the county of Montgomery and the State of Ohio, have invented certain new, original, and ornamental Design for Loop Antenna Housing or Similar Article, of which the following is a specification, reference being had to the accompanying drawing, forming part thereof, in which:

Fig. 1 is a side elevational view of a loop antenna housing showing my new design;

Fig. 2 is a top plan view; and

Fig. 3 is an end elevational view thereof as viewed from the blunt end.

The characteristic feature of my design resides in the surface ornamentation.

The present application is a continuation-in-part of my copending application, Serial No. D-86,073, filed on July 19, 1939, for "Streamline structure."

I claim:

The ornamental design for a loop antenna housing or similar article, substantially as shown and described.

WILLIAM P. LEAR.
